DESIGN FOR A PENCIL-CASE.

Design No. 13,021, dated July 4, 1882.

UNITED STATES PATENT OFFICE.

LE ROY W. FAIRCHILD, OF NEW YORK, N. Y.

DESIGN FOR A PENCIL-CASE.

SPECIFICATION forming part of Design No. 13,021, dated July 4, 1882.

Application filed May 18, 1882. Term of patent 7 years.

To all whom it may concern:

Be it known that I, LE ROY W. FAIRCHILD, of New York, in the county of New York and State of New York, have invented a Design 5 for a Pencil-Case, of which the following is a specification.

My design belongs to that class which are denominated "charms," and which usually consist of some fancy or ornamental article usually worn on a watch-chain.

The design in this case consists of a case the body of which is made in the form of a tea-pot, as shown in the accompanying photograph, forming a part of this specification.

15 This case or body A may be of the precise form shown, or any form or style in which tea-pots are usually made, and may have its surface ornamented by engraving or by raised figures, as may be preferred.

20 Within this case or body A, I arrange an extension-case, B, preferably of the kind known as a "magic movement," so that when the part B is drawn out it will cause the point e to protrude at the bottom of the case A, as shown. In

25 the photograph I have shown the point e as an ordinary pencil-point; but it is obvious that instead of the pencil-point any other small im-

plement may be substituted without changing the design.

The extension-tube B is provided at its upper end with a cap or head, c, which, when the extension-case is closed, fits down upon the top of the case or body A, and thus forms in appearance a cover for the tea-pot or case A.

By making the parts A, B, and c of different kinds of metal or different colors or shades of the same metal, or ornamenting the body A with raised or other figures of a different metal or color, the article may be made to present a very ornamental appearance. If desired, it 40 may have a ring attached either to the body A or its handle, or to the top c of the part B, for securing it to the watch or other chain.

I claim—

The design for a case for a pencil or similar 45 implement, consisting of the body A, made in the form of a tea-pot, and the extension-case B, provided with the cap or head c; to form a cover for the body A when closed, as shown and described.

LE ROY W. FAIRCHILD.
